UNITED STATES PATENT OFFICE.

LESTER R. WELLMAN, OF CHICAGO, ILLINOIS, ASSIGNOR TO FRIEDELEY VOSHARDT CO.,
OF CHICAGO, ILLINOIS, A CORPORATION OF ILLINOIS.

DESIGN FOR A LIGHTING-FIXTURE.

51,053.

Specification for Design. Patented July 17, 1917.

Application filed May 31, 1917. Serial No. 172,117. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Lighting-Fixture, of which the following is the specification, reference being had to the accompanying drawing, forming part thereof.

Fig. 2 is a side elevation.

Fig. 3 is a top or bottom view of the same.

I claim:

The ornamental design for a lighting fixture, as shown.

LESTER R. WELLMAN.
